UNITED STATES PATENT OFFICE.

AXEL ANDERSON, OF ST. PAUL, MINNESOTA, ASSIGNOR TO RUSSELL GRADER MANUFACTURING COMPANY, OF MINNEAPOLIS, MINNESOTA, A CORPORATION.

DRAFT-RIGGING.

1,153,007.

Specification of Letters Patent. Patented Sept. 7, 1915.

Application filed December 19, 1913. Serial No. 807,623.

To all whom it may concern:

Be it known that I, AXEL ANDERSON, citizen of the United States, resident of St. Paul, county of Ramsey, State of Minnesota, 5 have invented certain new and useful Improvements in Draft-Rigging, of which the following is a specification.

The object of this invention is to provide a draft connection by means of which the 10 pull will be transmitted directly to the work without passing through the axle.

A further object is to provide a draft connection which will relieve the frame of the machine from the strain to which it is 15 usually subjected in pulling the load.

A further object is to provide a draft connection which will be simple and economical in construction and very strong and durable.

The invention consists generally in various 20 constructions and combinations, all as hereinafter described and particularly pointed out in the claims.

In the accompanying drawings forming part of this specification, Figure 1 is a plan 25 view of a draft rigging embodying my invention, Fig. 2 is a side elevation, partially in section, of the same.

In the drawing, 2 represents the forward

axle, having carrying wheels 3. This axle 30 has bearings in a transverse I-beam 4. A casting 5 in the form of a bolster has an upper bracket 6 which embraces the upper portion of the I-beam and extends under the axle and is spaced from the upper bracket 35 to receive the rear end of the draft tongue 8 through which and said brackets a pin 9 is inserted. Upon the bolster 5 a channel bar 10 is arranged, having upwardly turned ends 11 which are secured to the frame 12.

40 A channel bar 13 extends across the channel bar 10 and has an upwardly turned portion secured to the frame 12 and a ring 14, T-shaped in cross section, is secured to the channel bar 13 and braces 15 and 16 connect the channel bar 13 with the frame 12. Bearings 17 in the form of segments of circles are mounted on the channel 4 and are 45 free to slide on the T-ring 14 as the axle and bolster are oscillated to steer the machine.

50 A king-bolt 18 passes down through the channel bar 10 and has a head at its lower end bearing on the bracket 7, and a coiled spring 19 between a washer 20 at the upper end of said pin and the bottom of the channel bar 13. This spring operates to hold the

bolster and the channel bar 11 in yielding engagement with one another. The king-bolt, as noted, is in the rear of the axle 2.

21 represents a flexible and adjustable connection between the lower end of the king-bolt and the frame of the conveyer 22 and an adjustable connection 23 is provided between the frame 24 to which the plow beam (not shown) is attached. These connections have a coupling 26 direct to the king-bolt and from the king-bolt the strain is communicated through the lower bracket of the bolster to the draft pole 8. A steering rigging 27 of ordinary construction is mounted on the draft pole and is operated by a steering post 70 60 65 70 75 80 85 90 95 100 105 110

28 having a wheel 29 on the frame of the machine. It will be noted that the king-bolt is independent of the axle and that the draft is applied directly to this bolt without subjecting the axle or the frame of the machine 75 to any strain.

In various ways the details of construction herein shown and described may be modified and still be within the scope of my invention.

I claim as my invention:

1. The combination, with a frame having a forward axle and carrying wheels and a bolster mounted on said axle, a king-bolt 80 85 90 95 100 105 110 pivotally connecting said frame and bolster, a draft tongue connected to said bolster, a draft connection for the lower end of said king-bolt, the pull being transmitted from said tongue through said king-bolt to said draft connection independently of said axle.

2. The combination, with a frame, an axle and carrying wheels therefor and a bolster mounted on said axle, of a king-bolt pivotally connecting said frame and bolster independently of said axle, a draft connection for said king-bolt, and a draft tongue having a direct connection through said bolster with said king-bolt.

3. The combination, with a forward axle having carrying wheels, of a transverse beam wherein said axle is mounted, a bolster having an upper and a lower bracket arranged to straddle said axle and beam, a draft tongue connected to said brackets, a frame having bearings on said bolster, a king-bolt passing through said bolster and pivotally connecting it with said frame, and a direct draft connection for said king-bolt.

4. The combination, with an axle having carrying wheels, of a bolster mounted there-

on and having forwardly projecting brackets arranged one above another and straddling said axle, a draft tongue connected to the forward portion of said brackets, a frame having bearings on said bolster, a king-bolt mounted in said frame and having a comparatively long bearing surface in said bolster in the rear of said axle, the pull of said draft tongue on said bolster being transmitted through said brackets to said king-bolt independently of said axle, and draft connections for the lower portion of said king-bolt.

5. The combination, with a forward axle and carrying wheels and a bolster mounted thereon, of a frame supported by said bolster, a king-bolt pivotally connecting said frame and said bolster, means having a draft connection with said bolster, a draft connection for said king-bolt, the draft being applied directly through said bolster to said king bolt.

6. The combination, with an axle and carrying wheels, of a bolster mounted thereon, a frame, a channel bar secured at its ends to said frame and its middle portion having a bearing on said bolster, a second channel bar extending transversely of said first

named bar and secured to said frame, segment rings mounted on said bolster and bars 20 to rotate one within the other, a king-bolt passing down through said channel bars and bolster, a spring interposed between the upper end of said king-bolt and said channel bars, and a draft connection for the 35 lower portion of said king-bolt.

7. The combination, with an axle and carrying wheels and a bolster, of a frame, a king-bolt pivotally connecting said frame with said bolster in the rear of said axle, the lower end of said bolt depending below the level of said axle, and a draft connection for said king-bolt.

8. The combination, with an axle and carrying wheels, of a frame, a king bolt for 45 said frame and axle, a draft tongue having a direct connection with said king bolt and draft connections having a direct connection through said king bolt with said draft tongue.

In witness whereof, I have hereunto set my hand this 2nd day of December, 1913.

AXEL ANDERSON.
